UNITED STATES PATENT OFFICE.

HENRY BERNHARD FURSTONBURG, OF SHREVEPORT, LOUISIANA, ASSIGNOR OF ONE-HALF TO OTTO H. BRUEHL, OF LEMSVILLE, LOUISIANA.

LATERAL TAKE-UP DEVICE FOR LOCOMOTIVE-AXLES.

1,202,701.

Specification of Letters Patent. Patented Oct. 24, 1916.

Application filed April 19, 1916. Serial No. 92,149.

To all whom it may concern:

Be it known that I, HENRY B. FURSTONBURG, a citizen of the United States, and a resident of Shreveport, in the parish of Caddo and State of Louisiana, have invented a certain new and useful Improvement in Lateral Take-Up Devices for Locomotive-Axes, of which the following is a specification.

13 My present invention relates generally to a device for taking up the longitudinal thrust of locomotive axles and preventing undue lateral play thereof with respect to the driving boxes, my object being to provide a device of this nature which will be inexpensive, both as to first cost and maintenance, which may be utilized without danger of displacement, and which will be extremely durable in use.

15 A further object of the invention is to provide a device of the above nature which may be installed and adjusted without dropping the wheels or tying up the locomotive and which may be provided with a 25 wear face renewable also without dropping the wheels or tying up the locomotive.

Other objects, and the advantages resulting therefrom, will be apparent from the following description of my invention, reference being had to the accompanying drawings, forming a part of this specification and in which—

Figure 1 is an elevation of an axle provided with my improvements, partly broken away and in section. Fig. 2 is a vertical cross section therethrough, taken substantially on line 2—2 of Fig. 1. Fig. 3 is a detail perspective view of my improvements detached, and with the sections thereof separated.

Referring now to these figures, my improvements are preferably installed and utilized in connection with a locomotive axle A having reduced ends A' upon the outer extremities of which the locomotive wheels B are secured, the driving boxes C being adjacent the inner faces of the wheels B.

My improvements as applied to the above parts consist of a take-up member adjacent each driving box C and including inner and outer sections 10 and 11 respectively, each section being formed of separable parts of which the parts of the section 10 are shown at 12 and 13 in Fig. 3 in particular

and the parts of the section 11 are shown at 14 and 15. The parts of each of the sections 10 and 11 are provided with abutting side flanges and are connected by bolts 16 passing through such flanges.

By reference to Fig. 1 it will be noted that the inner section 10 abuts at its inner end the adjacent annular shoulder A² of the axle at the inner end of its reduced portion A' upon which the particular member is mounted, and that, in addition to this abutment which effectively limits inward movement of the section 10 along the axle A, this section is keyed to the reduced portion A' of the axle by means of a key 17. It will also be noted that, each of the sections 10 and 11 is provided with a plurality of radially disposed set screws 18, by which it may be secured to the reduced portion of the axle upon which it is mounted, and that these sections are provided with abutting annular flanges 19 and 20 apertured for the reception of connecting bolts 21, the use of which permits longitudinal adjustment of the outer section 11 with respect to the inner section and the use of facing liners as seen at 22 in Fig. 1, between the sections resulting in their adjustable spacing and adjustment of the outer section 11 with respect to the adjacent driving box C.

The outer end of the section 11 has an annular flange 23 and this flange, as well as the flanges 19 and 20 of the two sections, may be reinforced by webs 24, one of which is provided with an inclined opening 25 for the reception of a suitable lubricant, and which may be either closed by a plug 26, or have mounted in connection therewith, a suitable grease cup, as well known for this purpose, the outer end of the opening 25 extending through the outer face of the flange 23. The outer face of the flange 23 may also be provided with a counterbore for the reception of a wear plate 27 to extend therebeyond and into direct engagement with the adjacent driving box C and which, though sectional as shown in Fig. 2, will be held in place in the counterbore when the parts are properly adjusted. Thus, by virtue of the fact that each of the sections is made of separately connected parts, the device may be applied and adjusted at all times without dropping the wheels B or tying up the locomotive in connection with which the axle A is mounted, the outer section 11 at

each side may be removed for renewal of the wear plate 27, and for its own adjustment by the interposition of more or less spacing liners 22 between the sections, without disturbing the rigidly connected inner section 10.

It will thus be seen that the device as proposed by my invention is not only economical, as to its initial cost, but may be maintained at all times at a small cost, and will be readily adjustable, durable, and highly effective for the purposes above mentioned.

I claim:—

1. A lateral take-up device of the character described, comprising the combination with a locomotive axle, of a take-up member thereon including inner and outer sections having flanged opposing ends, the inner section of which is immovably connected to the axle, and the outer section of which is adjustable on the axle, liners be-

tween said sections for adjustably spacing the same apart, and bolts for adjustably connecting said sections in spaced apart relation and extending through said flanges, 25 each of said sections comprising separably connected parts whereby to permit of its independent removal.

2. A lateral take-up device of the character described, comprising the combination 30 with a locomotive axle, of a take-up member thereon including inner and outer sections, means for immovably securing the inner section to the axle, adjustable connections between the said sections, said outer 35 section consisting of separably connected parts, and having a counterbore in its outer end, and a wear plate at the outer end of the outer section supported in the counterbore thereof.

HENRY BERNHARD FURSTONBURG.
